POWER OIL REMOVAL UNIT

Edward L. Wood, Detroit, Mich.

Application December 20, 1937, Serial No. 180,765

20 Claims. (Cl. 184—1.5)

This invention relates to power oil removal units adapted to remove oil from the crankcase of internal combustion engines of automobiles and the like.

5 One object of this invention is to provide improved, novel, positive, inexpensive means for quickly removing oil from the crank case of internal combustion engines and the like with a vacuum created in an oil receiver by suction from 10 the intake manifold of the said engine when running.

Another object of this invention is to provide 15 a connector fixed with respect to a motor vehicle having an air suction tube and an oil suction tube therefrom connected to the intake manifold and extending to the low point of the crankcase of the engine of the said vehicle respectively, the said connector being adapted to be hermetically engaged by oil receiving means which 20 applies suction from the air suction tube to the oil suction tube and thereby causes oil to be withdrawn from the said crankcase into the said oil receiving means.

Another object of the invention is to provide 25 a power oil removal unit comprising a connector permanently fixed with respect to a motor vehicle having an air suction tube and an oil suction tube therefrom connected to the intake manifold and extending to the low point of the crankcase 30 of the engine of the said vehicle respectively, the said air suction tube being normally closed at its unconnected end by a suitable valve, and oil receiving means adapted to be removably fixed in hermetically sealed relationship to the said connector over the unconnected ends of the said suction tubes and simultaneously open the said valve at the unconnected end of the said air suction tube whereby to create a vacuum in said oil receiving means for removing oil from the crank- 35 case of said engine thereinto.

Another object of this invention is to provide 40 a power oil removal unit comprising a connector permanently fixed with respect to a motor vehicle having an air suction tube and an oil suction tube 45 therefrom connected to the intake manifold and extending to the low point of the crankcase of the engine of the said vehicle respectively, the said air suction tube being normally closed at its unconnected end by a suitable valve, and oil receiving means adapted to be removably fixed in hermetically sealed relationship to the said connector over the unconnected ends of the said suction tubes and simultaneously open the said valve at the unconnected end of the said air suction 50 tube whereby to create a vacuum in said oil re-

ceiving means for removing oil from the crankcase of the said engine thereinto, the said oil receiving means having a vacuum relief aperture therethrough suitably located to admit of manual control of the vacuum created therein. 5

Other objects of the invention will become apparent by reference to the following detailed description taken in connection with the accompanying drawings, in which:

Fig. 1 is a view part in section and part in elevation showing the connector of a power oil removal unit embodying the invention mounted on and connected in operating relationship to an internal combustion engine with the oil receiver of the said oil removal unit suspended from and removably fixed to the said connector in hermetically sealed relationship thereto. 10

Fig. 2 is an enlarged detailed fragmentary sectional view through the connector of the power oil removal unit showing an oil receiver suspended therefrom, removably fixed in hermetically sealed relationship thereto, and simultaneously holding open the air valve normally closing the unconnected end of the air suction tube thereof. 20

Fig. 3 is a view part in section and part in elevation taken on the line 3—3 of Fig. 2. 25

Fig. 4 is a view similar to Fig. 3 showing a modified construction of means for supporting the oil receiver over the unconnected ends of the oil and air suction tubes. 30

Fig. 5 is a horizontal sectional view taken on the line 5—5 of Fig. 4. 35

Fig. 6 is a fragmentary vertical sectional view taken on the line 6—6 of Fig. 4.

Fig. 7 is a horizontal sectional view similar to Fig. 5 showing the normal position of the spring which compensates for the resiliency and wear of the sealing ring of the connector. 40

Fig. 8 is an enlarged cross sectional view similar to Fig. 2 showing the connector when not in use with a dust shield positioned thereover and prevented from rattling by the resilient sealing ring of the said oil receiver.

Fig. 9 is a detailed fragmentary sectional view similar to Fig. 2 showing the coupling of a sentinel type oil receiver to the connector of the power oil removal unit. 45

Fig. 10 is an enlarged sectional view taken on the line 10—10 of Fig. 9 showing a preferred means for the simultaneous chucking of the air and oil suction hoses from the sentinel type oil receiver to the means for coupling the sentinel type oil receiver to the said connector. 50

Fig. 11 is a view part in section and part in elevation showing a typical embodiment of a sen- 55

tinel type oil receiver adapted for use with the connector disclosed herein.

Referring now to the drawings wherein like numerals refer to like and corresponding parts throughout the several views, the embodiment of the invention disclosed therein comprises, a power oil removal unit composed of a connector 10 permanently mounted by means of a suitable bracket 11 on the block of an internal combustion engine 12. Although the connector of the power oil removal unit is disclosed herein secured on the block of an internal combustion engine it is contemplated that the connector may be mounted elsewhere if desired but fixed with respect to the said engine or the body of a motor vehicle propelled thereby. The said connector 10 has an air suction line 13 therefrom connected to a source of suction such as the intake manifold (not shown) of the said internal combustion engine 12. An oil suction line 14 from the connector 10 preferably extends through the upper portion of the crankcase 15 of the said internal combustion engine 12 to the low point 16 thereof. The said oil suction line 14 is preferably secured to and through the said crankcase 15 by such means as a split sleeve nut 17 which squeezes the said oil suction line 14 when the said nut is tightened into the said crankcase 15. A split spring lock washer 18 is preferably used between the head of the sleeve nut 17 and the crankcase 15 to prevent the said split sleeve nut 17 from becoming loosened by the vibration of the said internal combustion engine 12. An oil receiver 19 having a suitable spent oil container 20 threaded thereto is adapted to be supported from and positioned in hermetically sealed relationship to the said connector 10 over the unconnected ends of the said air suction line 13 and oil suction line 14 as best indicated in Fig. 1. A gasket 21 between the annular shoulder 22 of the said container 20 and the oil receiver 19 assures an air-tight coupling therebetween.

The novel construction of the connector 10 and the oil receiver 19 including the means for suspending the said oil receiver 19 into hermetically sealed relationship over the unconnected ends of the air suction line 13 and the oil suction line 14 is shown in detail in Figs. 2 and 3 while a modified construction of the said suspending means is shown in Figs. 4 to 7 inclusive. Fig. 8 shows the connector 10 when not in use having a dust shield positioned in antirattle relationship therover.

The front of the connector 10 is preferably formed disk shaped with an annular lip 23 therearound disposed forwardly therefrom. The said connector 10 is provided with a generally vertically disposed rearward protuberance to accommodate air and oil suction connections as hereinabove described. A centrally disposed boss 24 at the extreme rear of the said connector is bored and threaded at 25 for receiving the machine screw 26 by means of which the said connector 10 is secured to the bracket 11. A suitable lock washer 27 interposed between the bracket 11 and the head of the machine screw 26 prevents the said machine screw from loosening due to vibration of the lock of the internal combustion engine 12. A pair of tabs 28 projecting from the said boss 24 fit into complementary apertures formed in the said bracket 11 and prevent the said connector 10 from rotating with respect to the said bracket 11. A machine screw 29 and lock washer 30 is preferably used to secure the said bracket 11 to the engine block 12, see Fig. 1.

A tubular projection 31 formed integral with the connector 10 and extending radially upward therefrom frictionally receives the air suction tube 13 thereover whereby a permanent connection between the connector 10 and a source of suction is accomplished. The vertical bore 32 of the said tubular projection 31 extends downwardly from the top of the said connector 10 until its communicates with the horizontally disposed bore 33 preferably located on the vertical axis of the said connector 10 positioned above the center of the said connector 10 and extending rearwardly from the disk shaped face thereof, all as illustrated in Fig. 2.

A suitable air valve 34 seated in the base of a thimble 35 threaded in the horizontally disposed bore 33 is normally maintained in its closed position by the compression spring 36. The stem of the said air valve 34 is preferably shouldered as indicated in the drawings and has a plunger 37 riveted on the end thereof, the said plunger 37 is cylindrical shaped of a smaller diameter than the inside diameter of the said thimble 35 and has a plurality of radially outwardly disposed guides 38 integral therewith and coextensive therewith which centers the said plunger 37 within the said thimble 35. The compression spring 36 reacts against the bottom of the said thimble 35 and engages the inwardly disposed ends of the said guides 38 for constantly urging the air valve 34 into its closed position seated in the bottom of the said thimble 35.

A forwardly disposed tubular projection 39 formed integral with the said connector 10 preferably located on the vertical axis of the said connector 10 and spaced below the said air valve 34 serves as the unconnected end of the oil suction line 14. The horizontal bore 40 of the said forwardly disposed tubular projection 39 extends inwardly from the front of the said connector 10 until it communicates with a vertically disposed bore 41 preferably located on the vertical axis of the said connector 10 extending from the bottom of the said connector 10 upwardly a sufficient distance to communicate with the said horizontal bore 40. The bottom of the said vertically disposed bore 41 is suitably threaded at 42 to receive a flared tube fitting 43 onto which the flared end of the oil suction tube 14 is connected by means of a flared tube connector nut 44.

The bracket 11 is preferably extended up the back and across the top of the said connector 10 and is formed into a vertically disposed support 110 from which oil receiving means is removably suspended and positioned in hermetically sealed relationship over the unconnected ends of the said air and oil suction tubes 13 and 14 respectively. The said support 110 extends above the top of the said connector 10 and is spaced forward of the vertically disposed tubular projection 31 thereof. The horizontally disposed portion of the said bracket 11 which extends across the top of the said connector 10 is preferably provided with an aperture 45 through which the said vertically disposed tubular projection 31 of the said connector 10 is telescoped as best illustrated in Fig. 2. Although the support 110 is disclosed herein integral with the bracket 11, the said support 110 may be formed integral with the said connector 10 or it may be of a separate piece of material suitably secured to the said connector 10.

The said support 110 is suitably horizontally grooved near the top thereof to provide a pair of spaced vertically disposed tabs 46 adapted to

serve as guides for accurately positioning oil receiving means into hermetically sealed relationship against the said connector 10 over the unconnected ends of the air suction line 13 and the oil suction line 14 as hereinafter described.

An annular sealing ring 47 of rubber or other suitable material is suitably secured or positioned against the front of the said connector 10 radially within the forwardly disposed annular lip 23 therearound.

The oil receiver 19 is preferably formed elbow shaped as best illustrated in Fig. 1 and has the lower bell shaped depending end 48 thereof internally threaded to permit the same to be secured in hermetically sealed relationship to the complementarily threaded neck 49 of the container 20. The throat of the oil receiver 19 is preferably provided with a plurality of external longitudinally disposed circumferentially spaced ribs 50 as indicated in Figs. 1 and 3 to aid in cooling the exterior surface thereof which often becomes heated from hot oil passing therethrough.

The laterally disposed open annular end of the said oil receiver 19 is of such a diameter as will permit the same to register with the sealing ring 47 of the said connector 10 and is preferably provided with an annular groove 51 to assure a hermetically sealed joint between the said oil receiver 19 and the connector 10 when positioned thereagainst.

The said oil receiver 19 is preferably provided with a ridge 52 disposed inwardly of the annularly grooved laterally disposed open end thereof sufficiently close to the said laterally disposed open end of the oil receiver 19 to cause oil drawn by suction from the bore 40 of the said tubular projection 39 which serves as the unconnected end of the oil suction line 14 to spew or drip down the throat of the said connector 19 thereby preventing an accumulation of oil in the end of the oil receiver 19 adjacent to the annular sealing ring 47 of the said connector 10 when the oil removal unit is in use.

The said oil receiver 19 is preferably provided with a hooked shaped strap hanger 53 on the outside of the top thereof and an air valve contactor 54 on the inside of the top thereof both of which are preferably secured to the said oil receiver by such means as the through rivets 55 as best illustrated in Fig. 2. The said hooked shaped strap hanger 53 is so formed as to engage the said oil receiver support 110 vertically disposed on top of the said connector 10 between the spaced vertically disposed tabs 46 of the said support 110 as indicated by the dot and dash lines in Fig. 1 when the oil receiving means is being positioned in operating relationship with the said connector 10. The said oil receiver 19 is accurately guided by the cooperation of the said hooked shaped strap hanger 53 with the said support 110 into hermetically sealed relationship with the connector 10 with the laterally disposed annular grooved open end of the said oil receiving means 19 in sealed engagement against the annular sealing ring 47 of the said connector 10 as indicated by the full lines in Fig. 1 and as shown in detail in Fig. 2, at which time the said air valve contactor 54 of the said oil receiving means 19 has contacted the air valve 34 of the said connector 10 and has opened the same as indicated in Fig. 2.

The said oil receiver 19 is preferably provided with a suitably disposed vacuum relief aperture 56 therethrough which prevents a vacuum from being built up in the oil receiver 19 and its container 20 unless the said vacuum relief aperture

is plugged up by the finger or thumb of the operator of the power oil removal unit.

Although the connector 10 has been shown and described with the unconnected end of the air suction line 13 and the unconnected end of the oil suction line 14 horizontally disposed, it is readily observed that, if the connector 10 is mounted or constructed so that the unconnected ends of the air suction line 13 and the oil suction line 14 are otherwise disposed and if the unconnected end of the oil suction line 14 is not positioned so that oil spewing therefrom will enter the unconnected end of the air suction line 13, the device will operate perfectly requiring but a simple change in the shape of the oil receiver 19 to accommodate it to any altered disposition or location of the unconnected ends of the air suction line 13 and the oil suction line 14 or to any rearrangement of the construction of the connector 10 per se. In rearranging the construction of the connector 10 and correspondingly changing the shape of the oil receiver 19 any suitable means may be used for removably fixing the oil receiving means in hermetically sealed relationship to the said connector 10 and over the unconnected ends of the said air suction tube 13 and oil suction tube 14.

The outer periphery of the forwardly disposed annular lip 23 of the said connector 10 is provided with diametrically opposite preferably cylindrical tabs 57 by means of which a cup shaped dust shield 58 provided with suitable diametrically oppositely disposed bayonet slots is removably secured over the front of the said connector 10 as best illustrated in Fig. 8. It will be noted that the shape of said cup shaped dust shield 58 is such as will engage the outwardly disposed annular face of the said annular sealing ring 47 and slightly compress the same whereupon the said sealing ring 47 constantly urges the said dust shield 58 in tensional relationship to the said tabs 57 whereby the said dust shield 58 is prevented from rattling when the connector 10 is vibrated by the engine 12.

Referring now to Figs. 4 to 7 inclusive, the modified construction of means for supporting the oil receiver 19 over the unconnected ends of the oil and air suction tubes 13 and 14 respectively shown therein compensates for the resiliency and any wear of the sealing ring 47 of the connector 10 and thereby assures a perfect hermetic seal at all times between the annularly grooved end 51 of the oil receiver 19 and the annular sealing ring 47 of the said connector 10. The vertically disposed support 1100 is identical in every respect to the vertically disposed support 110 shown in Figs. 2 and 3 except that it is not formed integral with the bracket 11 but is secured to the top of the connector 10 by such suitable means as the machine screws 59. The hooked shaped strap hanger 530 is similar to the hook shaped strap hanger 53 disclosed in Fig. 2 except that it is provided with a horizontally disposed portion 531 adapted to slide over the grooved top of the said support 1100 between the spaced vertically disposed tabs 46 thereof. The said support 1100 is provided with a pair of vertically oppositely diagonally disposed slots 60 which accommodate a bow-type spring 61 as best illustrated in Fig. 7. The said bow-type spring 61 is suitably crimped at its extreme ends 62 for retaining the same positioned in the said slot 60 of the support 1100.

When the oil receiver 19 equipped with a hooked shaped strap hanger 530 having a hori-

zontally disposed portion 531 as hereinbefore described is engaged over the said support 1100, the vertically disposed hooked portion 532 of the said hooked shaped strap hanger 530 engages the 5 bow-type spring 61 of the said support 1100 which spring 61 permits the said oil receiver 19 to be suspended from the said support 1100 at a suitable place along the horizontally disposed portion 531 of the said hook shaped strap hanger 10 530 in accordance with the resiliency and wear of the annular sealing ring 47 thereby causing the annularly grooved face 51 of the said oil receiver 19 to engage the said annular sealing ring 47 of the said connector 10 with substantially 15 equal horizontal pressure therearound. Construction not shown in the fragmentary Figs. 4 to 7 inclusive is preferably similar in every respect to the construction shown in detail in Figs. 2 and 3.

The embodiment of the power oil removal unit 20 disclosed in Figs. 9 to 11 inclusive is similar to the embodiment of the power oil removal unit disclosed in Figs. 1, 2, 3 and 8 except that a sentinel type oil receiver 63 is used instead of the portable oil receiver 19 and that an underground 25 spent oil container or tank 64 is substituted for the oil container 20. The said sentinel type oil receiver 63 has an air suction hose 65 and an oil suction hose 66 extending therefrom to a suitable coupler 67 which is adapted to engage the connector 10 in such a manner as to apply suction 30 from the air suction tube to the oil suction tube and cause oil to be withdrawn from the oil suction tube into the said sentinel type oil receiver 63.

35 A suitable valve 68 is provided in the drain line 69 between the said sentinel type oil receiver 63 and the underground spent oil container 64 to permit the sentinel type oil removal unit to operate without the necessity of building up a vacuum in the underground spent oil container 64 when the said valve 68 is closed. By closing off the underground spent oil container 64 from the sentinel type oil receiver 63 when the oil removal unit is in use, a considerable time is saved in 40 applying suction from the air suction line 13 to the oil suction line 14 and creating a vacuum in the said oil receiver 63 for causing oil to be withdrawn from the crankcase of an internal combustion engine into the said sentinel type oil receiver 63. After the sentinel type oil receiver 63 is filled with spent oil from the crankcase of an 45 internal combustion engine, the said sentinel type oil receiver 63 may be emptied by opening the said valve 68 in the said drain line 69 whereupon oil from the sentinel type oil receiver 63 50 drains through the said drain line 69 into the underground spent oil container 64.

55 It is therefore observed that the operation of the sentinel type oil removal unit disclosed in Figs. 9 to 11 inclusive is precisely the same as the operation of the portable type oil removal unit disclosed in Figs. 1, 2, 3 and 8 except that a spent oil container 64 of the sentinel type oil receiver 63 may be temporarily disconnected or sealed off from the said sentinel type oil receiver 63 while the sentinel type oil removal unit is in use whereas no means is provided for disconnecting the container 20 of the portable oil receiver 19 disclosed in Fig. 1 while the portable oil removal unit is in use.

70 The connector 10 disclosed in Fig. 9 is similar in every respect to the connector 10 disclosed in Figs. 2, 3 and 8 and hereinbefore described in detail.

75 The coupler 67 shown in detail in Fig. 9 is

preferably a generally annular shaped casting having a flared end of such a diameter and suitably grooved at 70 to register in hermetically sealed relationship with the annular sealing ring 47 of the said connector 10 when positioned 5 thereagainst. The said coupler 67 has concentrically spaced air and oil suction hose sleeves 71 and 72 respectively formed integral therewith but centered on the vertical axis thereof below the center of the said annular flared grooved end 10 70 thereof a sufficient distance to permit the said oil hose sleeve 72 to be in alignment with the unconnected end 39 of the oil suction line 14 of the connector 10 when the said coupler 67 is properly positioned against the said connector 15 10.

A suitable washer and guide 73 is positioned in the cup 74 integrally formed in the said coupler 67 at one end of the said oil suction hose sleeve 72 for assuring an oil tight connection between 20 the oil suction hose sleeve 72 and the unconnected end of the oil suction line 14 of the connector 10 when the said coupler 67 is positioned in hermetically sealed relationship against the said connector 10.

The oil suction hose 66 is preferably frictionally engaged over the end of the said oil suction hose sleeve 72 opposite the cupped end thereof in telescopingly spaced relationship within the said air suction hose sleeve 71 as best illustrated in 30 Fig. 9. The air suction hose 65 which has an inside diameter considerably larger than the outside diameter of the oil suction hose 66 and through which the said oil suction hose 66 is telescoped, is preferably frictionally engaged and 35 secured over the air suction hose sleeve 71 as hereinafter described.

The said air suction hose 65 is preferably clamped to the said air suction hose sleeve 71 by means of tapered semi-crescent shaped wedges 40 75 over which a complementarily tapered ring 76 is drawn by threading the said tapered ring 76 onto the threaded end 77 of the said coupler 67. Pliable gaskets 78 and 79 provide means for hermetically sealing the joints between the wedges 75, and between the wedges 75 and the tapered ring 76, respectively. A key 80 preferably integral with the said coupler 67 positioned on the vertical axis thereof prevents the said semi-crescent shaped tapered wedges 75 from 45 rotating within the said complementarily tapered ring 76 when the said wedges are being tightened 50 against or loosened from the air suction hose 65 and the air suction hose sleeve 71.

A short length of spring wire hose guard 81 is 55 preferably telescoped over the air suction hose 65 and securely clamped thereto by a suitable clamp 82 positioned around the projecting end of the said air suction hose sleeve 71 as best 60 illustrated in Fig. 9. The said spring wire hose guard 81 prevents the air suction hose 65 from kinking at the end of the coupler 67. A suitable air passage aperture 83 is provided through the air suction hose sleeve 71 as indicated in Fig. 9 65 to permit air to be drawn from the air suction hose 65 through the air suction line 13 when the coupler 67 is positioned in hermetically sealed relationship to the annular sealing ring 47 of the said connector 10 and when the air valve 34 normally closing the unconnected end of the said 70 air suction line 13 at the connector 10 is opened as hereinafter described.

The said coupler 67 is preferably provided with a hook shaped strap hanger 84 on the outside of the top thereof and an air valve contactor 85 on 75

the inside of the top thereof both of which are secured to the said coupler 67 by such means as the through rivets 86 as best illustrated in Fig. 9. The said hook shaped strap hanger 84 is so formed as to engage the said oil receiver support 110 vertically disposed on the top of the said connector 10 between the spaced vertically disposed tabs 46 of the said support 110 when the coupler 67 is being positioned in operating relationship with the connector 10. The said coupler 67 is accurately guided by the cooperation of the said hook shaped strap hanger 84 with the said support 110 into hermetically sealed relationship with the connector 10 with the laterally disposed annular grooved open end of the said coupler 67 in sealed engagement with the annular sealing ring 47 of the said connector 10, at which time the said air valve contactor 85 of the said coupler 67 has contacted the air valve 34 of the said connector 10 and has opened the same as indicated in Fig. 9.

Although not shown, the said coupler 67 may be provided with a suitably disposed vacuum relief aperture therethrough similar to the vacuum relief aperture 56 of the said oil receiver 19 for preventing a vacuum from being built up in the sentinel type oil receiver 63 unless the said vacuum relief aperture is plugged up by the finger or thumb of the operator of the power oil removal unit.

The sentinel type oil receiver 63 is preferably formed bottle shaped of glass having a threaded upper neck 87 onto which the air suction hose 65 is hermetically connected by a suitably threaded cap 88 through which the said oil suction hose 66 centrally depends a short distance into the said oil receiver 63 in telescopingly spaced relationship thereto. The said oil receiver 63 is preferably provided with a tapered lower neck 89 which is frictionally sealed within the funnel shaped connection 90 disposed on the top of the drain line 69. A compressible tapered washer 91 assures a hermetic seal between the said tapered lower neck 89 of the said oil receiver 63 and the said funnel shaped drain line connection 90.

The said oil receiver 63 is preferably supported on a tubular metal post 92 having a metal base 93 welded thereto, which base is in turn suitably secured to a concrete curb 94. The top of the said tubular metal post 92 is preferably provided with an annular dish shaped oil receiver support 95 onto which the said oil receiver 63 is positioned with a suitable annular compressible dish shaped gasket 96 therebetween.

A suitable ornamental cap 97 preferably having a sign globe 98 thereon and having an annular dome shaped bottom 99 is positioned over the top of the said oil receiver 63 with a compressible annular dome shaped gasket 100 therebetween. The said cap 97 is preferably provided with a sleeve 101 at one side thereof through which the air suction hose 65 enters. A short length of spring wire hose guard 102 adapted to prevent the said air suction hose 65 from kinking at the said sleeve 101 is secured around the said hose 65 and anchored to the said sleeve 101 by such means as an internally circumferentially scored anchorage sleeve 103 threaded over the said sleeve 101 of the said ornamental cap 97.

The said annular dome shaped bottom 99 of the said ornamental cap 97 is provided with a plurality of circumferentially spaced radially projecting vertically disposed anchorage lugs 104 having a vertically disposed threaded bore in the bottom thereof to accommodate the threaded

end of the anchorage rods 105. The said annular disk shaped oil receiver support 95 is provided with a plurality of like circumferentially spaced vertically disposed radially projecting anchorage lugs 106 having a vertically disposed threaded bore in the top thereof to accommodate the threaded end of the said anchorage rods 105. The threads at the opposite ends of the said anchorage rods 105 are oppositely pitched and the threads of the vertical bores of the anchorage lugs 104 and 106 respectively are oppositely pitched so that when the said anchorage rods 105 are threaded thereinto the said anchorage rods 105 will tensionally secure the said sentinel type oil receiver 63 in assembled relationship on its pedestal 92 with the ornamental cap 97 thereover as best illustrated in Fig. 11.

The tubular metal post 92 of the said sentinel type oil receiver 63 is preferably slotted at 107 through which the operating lever 108 of the valve 68 of the drain line 69 projects. When the said drain valve lever 108 is in the upward position as indicated by the full lines in Fig. 11 the sentinel type oil removal unit is ready to operate without the necessity of building a vacuum in the underground spent oil container 64. After oil has been removed from the crankcase of an internal combustion engine to the sentinel type oil receiver 63 and the said oil receiver 63 is filled with spent oil, the valve 68 in the drain line 69 between the oil receiver 63 and the underground spent oil container 64 is opened by moving the drain valve lever 108 to the position indicated by the dotted lines in Fig. 11 whereupon the said oil receiver 63 is emptied by gravity into the underground spent oil container 64.

It is readily observed from the foregoing description and the accompanying drawings that when a motor vehicle is equipped with a connector 10 embodying the invention, the motorist may remove spent oil from the crankcase of the internal combustion engine of the said motor vehicle when the said engine is running by positioning the portable oil receiver 19 having a spent oil container 20 connected thereto over the unconnected ends of the said air suction line 13 and oil suction line 14 as hereinbefore described, or, the motorist may drive into a gasoline station equipped with a sentinel type oil receiver 63 and have oil removed from the crankcase of his engine while the engine is running by connecting the said sentinel type oil receiver 63 over the unconnected ends of the air suction line 13 and the oil suction line 14 of the connector 10 by means of the coupler 67 as hereinbefore described. In either event, oil is removed from the crankcase of the internal combustion engine of the said vehicle with a vacuum created in an oil receiver by suction from the intake manifold of the said engine of the said vehicle when running.

Although but two embodiments of the invention and one modification thereof have been disclosed and described in detail, it will be understood that various changes including the size, shape, arrangement and details of the various parts thereof may be made without departing from the spirit of the invention, and it is not my intention to limit the scope of the invention other than by the terms of the appended claims.

I claim:

1. In combination with a motor vehicle, a connector mounted on said motor vehicle, an air suction tube connected to the intake manifold of the engine of the said motor vehicle, an oil

suction tube communicating with the low point of the crankcase of the said engine, the unconnected ends of the said suction tubes being mounted on the said connector, the said connector being adapted to support and position means for applying suction from the said air suction tube to the said oil suction tube in hermetically sealed relationship over the unconnected ends of said suction tubes whereby oil is removed from the crankcase of the said engine into an oil receiver.

2. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, and an oil receiver adapted to be removably fixed in hermetically sealed relationship over the said unconnected ends of the said suction tubes whereby to apply suction from the air suction tube to the oil suction tube which removes oil from the crankcase of the said engine into the said oil receiver.

3. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, and supporting means fixed with respect to the said connector from which oil receiving means may be removably suspended and positioned in hermetically sealed relationship over the unconnected ends of the said suction tubes whereby suction is applied from the air suction tube to the oil suction tube which removes oil from the crankcase of the said engine into the said oil receiver.

4. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a support for oil receiving means on said connector, a sealing ring on said connector, and oil receiving means adapted to be suspended from said support in hermetically sealed relationship against said sealing ring and apply suction from the said air suction tube to the said oil suction tube whereupon oil is removed from the crankcase of the said engine into the said oil receiving means.

5. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a support for oil receiving means on said connector, a sealing ring on said connector positioned around the unconnected ends of said suction tube, an oil receiver, and means on said oil receiver adapted to cooperate with said oil receiver support to accurately suspend said oil receiver in hermetically sealed relationship over the unconnected ends of said suction tubes against said sealing ring where-

upon oil is removed from the crankcase of the said engine into the said oil receiver.

6. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a sealing ring on said connector positioned around the unconnected ends of the said suction tubes, oil receiving means, and means for accurately suspending said oil receiving means in hermetically sealed relationship over the unconnected ends of said suction tubes and against said sealing ring on said connector comprising a support having a pair of spaced guides integral therewith on said connector and a hanger secured to said oil receiving means formed to engage said support between 20 said guides.

7. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a sealing ring on said connector positioned around the unconnected ends of the said suction tubes, oil receiving means, and means for accurately suspending said oil receiving means in hermetically sealed relationship over the unconnected ends of said suction tubes and against said sealing ring on said connector comprising a support having a pair of spaced guides integral therewith on said connector and a hanger secured to said oil receiving means formed to engage said support between 30 said guides, the said suspending means being 35 adapted to compensate for resiliency and wear 40 of the said sealing ring.

8. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a sealing ring on said connector positioned around the unconnected ends of the said suction tubes, oil receiving means, and means for accurately suspending said oil receiving means in hermetically sealed relationship over the unconnected ends of said suction tubes and against said sealing ring on said connector comprising a support having a pair of spaced guides integral therewith on said connector and a hanger secured to said oil receiving means formed to engage said support between 50 55 said guides.

9. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a sealing ring on said connector positioned around the unconnected ends 70 of the said suction tubes, oil receiving means, and means for accurately suspending said oil receiving means in hermetically sealed relationship over the unconnected ends of said suction tubes and against said sealing ring on said con- 75

5 nector comprising a support having a pair of spaced guides integral therewith on said connector and a hangar secured to said oil receiving means formed to engage said support between 5 said guides, the said suspending means being adapted to compensate for resiliency and wear of the said sealing ring.

10. In combination with a motor vehicle, a connector mounted on said motor vehicle, an air 10 suction tube connected to the intake manifold of the engine of the said motor vehicle, an oil suction tube communicating with the low point of the crankcase of the said engine, the unconnected ends of the said suction tubes being 15 mounted on the said connector, an air valve normally closing the unconnected end of the said air suction tube, and an oil receiver adapted to be removably fixed in hermetically sealed relationship over the said unconnected ends of the 20 said suction tubes and hold the said air valve open whereby to apply suction from the air suction tube to the oil suction tube which removes oil from the crankcase of the said engine into the said oil receiver.

25. 11. In combination with a motor vehicle, a connector mounted on said motor vehicle, an air suction tube connected to the intake manifold of the engine of the said motor vehicle, an oil suction tube communicating with the low point 30 of the crankcase of the said engine, the unconnected ends of the said suction tubes being mounted on the said connector, an air valve normally closing the unconnected end of the said air suction tube, and supporting means fixed with 35 respect to the said connector from which oil receiving means is removably suspended and positioned in hermetically sealed relationship over the unconnected ends of the said suction tubes and against said air valve whereby the said 40 air valve is opened and suction is applied from the air suction tube to the oil suction tube which removes oil from the crankcase of the said engine into the said oil receiver.

12. In a power oil removal unit, in combination, 45 a connector mounted on a motor vehicle, an air suction tube connected to the intake manifold of the engine of the said motor vehicle, an oil suction tube communicating with the low point of the crankcase of the said engine, the unconnected ends of the said suction tubes being 50 mounted on the said connector, and an oil receiver adapted to be removably fixed in hermetically sealed relationship over the said unconnected ends of the said suction tubes whereby 55 to apply suction from the air suction tube to the oil suction tube which removes oil from the crankcase of the said engine into the said oil receiver, the said oil receiver having a vacuum relief aperture therethrough which prevents a 60 vacuum from being built up in said oil receiver until the said aperture is plugged by the operator of the said oil removal unit.

13. In a power oil removal unit, in combination, 65 a connector mounted on a motor vehicle, an air suction tube connected to the intake manifold of the engine of the said motor vehicle, an oil suction tube communicating with the low point of the crankcase of the said engine, the unconnected ends of the said suction tubes being 70 mounted on the said connector, a sealing ring on said connector positioned around the unconnected ends of the said suction tubes, and oil receiving means including means for accurately suspending said oil receiving means in hermetically sealed relationship over the unconnected

7 ends of said suction tubes and against said sealing ring on said connector comprising a support having a pair of spaced guides integral therewith on said connector and a hangar secured to said oil receiving means formed to engage said support between said guides, the said oil receiver having a vacuum relief aperture therethrough which prevents a vacuum from being built up in said oil receiver until the said aperture is plugged by the operator of the said oil removal unit. 10

14. In a power oil removal unit, in combination, 15 a connector mounted on a motor vehicle, an air suction tube connected to the intake manifold of the engine of the said motor vehicle, an oil suction tube communicating with the low point of the crankcase of the said engine, the unconnected ends of the said suction tubes being mounted on the said connector, an air valve normally closing the unconnected end of the said air suction tube, and an oil receiver adapted to be removably fixed in hermetically sealed relationship over the said unconnected ends of the said suction tubes and hold the said air valve open whereby to apply suction from the air suction tube to the oil suction tube which removes 20 oil from the crankcase of the said engine into the said oil receiver, the said oil receiver having a vacuum relief aperture therethrough which prevents a vacuum from being built up in said oil receiver until the said aperture is plugged by the 25 operator of the said oil removal unit.

15. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a support for coupling means on said connector, a sealing ring on said connector, an oil receiver, an air suction hose and an oil suction hose hermetically connected at one end to the upper end of said oil receiver, and a coupling means on the free ends of said air and oil suction hoses adapted to be suspended from said connector and couple the said air and oil suction hoses to said connector in hermetically sealed relationship against said sealing ring and the unconnected end of said oil suction tube whereby suction is applied from the air suction tube to the oil suction tube whereupon oil is removed from the crankcase of the said engine into the said oil receiver. 35

16. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, an air valve normally closing the unconnected end of said air suction tube, a support for coupling means on said connector, a sealing ring on said connector, an oil receiver, an air suction hose and an oil suction hose hermetically connected at one end to the upper end of said oil receiver, and a coupling means on the free ends of said air and oil suction hoses adapted to be suspended from said connector and simultaneously open said air valve and couple the said air and oil suction hoses to said connector in hermetically sealed relationship against the said sealing ring and the unconnected end of said oil suction tube whereby suction is applied from the air suction tube to the oil suction tube where- 40 45 50 55 60 65 70 75

upon oil is removed from the crankcase of the said engine into the said oil receiver.

17. In combination with a motor vehicle, a connector mounted on said motor vehicle, an air suction tube connected to the intake manifold of the engine of the said motor vehicle, an oil suction tube communicating with the low point of the crankcase of the said engine, the unconnected ends of the said suction tubes being mounted on the said connector, a support for coupling means on said connector, a sealing ring on said connector, an oil receiver, an air suction hose connected at one end to the upper end of said oil receiver, an oil suction hose having its outside diameter smaller than the inside diameter of said air suction hose telescoped therein and extending into said oil receiver, and a coupling means on the free ends of said air and oil suction hoses adapted to be suspended from said connector and couple the said air and oil suction hoses to said connector in hermetically sealed relationship against said sealing ring and the unconnected end of said oil suction tube whereby suction is applied from the air suction tube to the oil suction tube whereupon oil is removed from the crankcase of the said engine into the said oil receiver.

18. A power oil removal unit, in combination, a connector mounted on a motor vehicle, an air suction tube connected to the intake manifold of the engine of the said motor vehicle, an oil suction tube communicating with the low point of the crankcase of the said engine, the unconnected ends of the said suction tubes being mounted on the said connector, an air valve normally closing the unconnected end of said air suction tube, a support for coupling means on said connector, a sealing ring on said connector, an oil receiver, an air suction hose connected at one end to the upper end of said oil receiver, an oil suction hose having its outside diameter smaller than the inside diameter of said air suction hose telescoped therein and extending into said oil receiver, and a coupling means on the free ends of said air and oil suction hoses adapted to be suspended from said connector and simultaneously open said air valve and couple the said air and oil suction hoses to said connector in hermetically sealed relationship against said sealing ring and the unconnected end of said oil suction tube whereby suction is applied from the air suction tube to the oil suction tube whereupon oil is removed from the crankcase of the said engine into the said oil receiver.

19. A power oil removal unit, in combination, a connector mounted on a motor vehicle, an air suction tube connected to the intake manifold of the engine of the said motor vehicle, an

oil suction tube communicating with the low point of the crankcase of the said engine, the unconnected ends of the said suction tubes being mounted on the said connector, an air valve normally closing the unconnected end of said air suction tube, a support for coupling means on said connector, a sealing ring on said connector, an oil receiver, an air suction hose connected at one end to the upper end of said oil receiver, an oil suction hose having its outside diameter smaller than the inside diameter of said air suction hose telescoped therein and extending into said oil receiver, and a coupling means on the free ends of said air and oil suction hoses adapted to be suspended from said connector and simultaneously open said air valve and couple the said air and oil suction hoses to said connector in hermetically sealed relationship against said sealing ring and the unconnected end of the said oil suction tube whereby suction is applied from the air suction tube to the oil suction tube whereupon oil is removed from the crankcase of the said engine into the said oil receiver, the said coupling means and support therefor being adapted to compensate for resiliency and wear of the said sealing ring.

20. A power oil removal unit, in combination, a connector mounted on a motor vehicle, an air suction tube connected to the intake manifold of the engine of the said motor vehicle, an oil suction tube communicating with the low point of the crankcase of the said engine, the unconnected ends of the said suction tubes being mounted on the said connector, an air valve normally closing the unconnected end of said air suction tube, a support for coupling means on said connector, a sealing ring on said connector, a sentinel type oil receiver, an air suction hose connected at one end to the upper end of said oil receiver, an oil suction hose having its outside diameter smaller than the inside diameter of said air suction hose telescoped therein and extending into said oil receiver, and a coupling means on the free ends of said air and oil suction hoses adapted to be suspended from said connector and simultaneously open said air valve and couple the said air and oil suction hoses to said connector in hermetically sealed relationship against said sealing ring and the unconnected end of the said oil suction tube whereby suction is applied from the air suction tube to the oil suction tube whereupon oil is removed from the crankcase of the said engine into the said oil receiver, the said coupling means and support therefor being adapted to compensate for resiliency and wear of the said sealing ring.

EDWARD L. WOOD.
